UNITED STATES PATENT OFFICE

VERE B. BROWNE, OF BRACKENRIDGE, PENNSYLVANIA

ANNEALING

Original application filed May 28, 1927, Serial No. 194,927. Divided and this application filed September 26, 1929. Serial No. 395,224.

This invention relates to the manufacture of magnetic alloy sheets and more particularly to the annealing of relatively thin sheets of silicon iron or so called silicon steel for use in the manufacture of electrical apparatus, and this application is a division of my copending application Serial No. 194,927, filed May 28, 1927.

In the annealing of light gauge silicon iron or so called steel sheets for use in the manufacture of electrical apparatus, it has been shown that if the correct temperature is obtained and the time of annealing is sufficient, better results are obtained by annealing the sheets singly than in stacks as in standard box annealing operation.

Obviously the best results, therefore, should be obtained by annealing in a continuous furnace in which the sheets are charged at one end of the furnace and passed through a correct temperature zone and at a rate of speed such as to give the necessary time element to the annealing. Such a furnace can be made sufficiently long to permit a cooling zone through which sheets pass after they are annealed so that the sheets can be cooled after annealing and discharged at a relatively low temperature.

It would appear that a continuous process besides being economical ought to give to the sheets excellent electrical qualities. Unfortunately, however, such is not the case with those continuous processes heretofore practiced with which I am familiar. Silicon iron or steel sheets of light gauge when annealed in any of the continuous furnaces with which I am familiar become warped or buckled and unsuitable for use in the manufacture of electrical apparatus. Flatness is most important in sheets for use in the manufacture of electrical apparatus.

It has been found that in order to obtain magnetic alloy sheets of the highest quality it is necessary during the annealing thereof to prevent the gases given off from the sheets during the anneal from being reabsorbed.

An object of this invention is to provide an apparatus for the annealing of magnetic

alloy sheets by means of which the sheets are not only maintained flat during the anneal but are delivered from the anneal flat and with a minimum amount of occluded gases.

A further object of this invention is to provide an apparatus for the annealing of magnetic alloy sheets in which the sheets during the anneal and subsequent cooling are subjected to flattening strains of sufficient intensity to overcome the distorting strains produced in the sheets during rolling and during cooling after annealing.

A still further object of this invention is to provide an apparatus for the annealing of magnetic alloy sheets in which thorough ventilation of the sheets during annealing and subsequent cooling is obtained whereby the gases given off from the sheets during annealing are rapidly carried out of contact with the sheets.

These and other objects which will be apparent to those skilled in this particular art are accomplished by means of the apparatus illustrated in the accompanying drawings and described in detail in the specification. In the drawings, Figure 1 is a perspective partially broken-away view of an annealing apparatus embodying one form of this invention, and Fig. 2 is a transverse sectional view, partly broken away, through the apparatus illustrated in Fig. 1.

In carrying out this invention, an annealing chamber of any desired type or form can be employed. The sheets to be annealed are passed through this annealing chamber, or under some circumstances may merely be positioned therein, where they will be subjected to the annealing temperature. Each sheet is so supported as to be separated from every other sheet in the chamber so that perfect ventilation may be obtained around each of the individual sheets. If desired, the sheets may be in groups of two or more, as illustrated. In order to remove the buckles due to rolling and to prevent any distortion of the sheets during cooling after annealing each sheet is subjected to an externally applied strain which places the sheet under such tension as to insure its

being brought to a perfectly flat condition as soon as softened by the annealing heat and maintained in that condition throughout the process. In the illustrated embodiment of the method and apparatus, this is accomplished by subjecting the individual sheets to stretching or pulling action at their opposite ends and which is of sufficient intensity to flatten the softened sheets and hold them in flattened condition until their temperature is lowered to the necessary point.

The particular form of apparatus illustrated in the accompanying drawings, includes a furnace formed from a plurality of similar sections 5 having recesses 6 so formed in the inner walls thereof that when two sections are positioned opposite to each other the oppositely positioned recesses co-operate to provide an annealing chamber 7 having slots 8 and 9 extending through the top and bottom, respectively, of the furnace, and communicating with the annealing chamber. In the form shown for illustration the furnace is heated by electric resistance elements 10 but it will be apparent that any type of heater can be employed. It will also be apparent that an annealing chamber and furnace of any desired length can be provided by associating together a sufficient number of individual furnace sections.

Mechanism is provided for passing the sheets to be annealed through the annealing chamber. As illustrated, this mechanism includes a track 11 which extends longitudinally above the furnace in line with the slot 8 communicating with the upper end of the combustion chamber. Trolleys 12 are supported upon the track by rollers 13 and each trolley has a hanger 14 secured thereto and extending downwardly below the top of the annealing chamber. Each hanger 14 has a plurality of upwardly inclined prongs 15 on each side thereof for the purpose of supporting a pair of sheets 16 to be annealed.

In order to prevent distortion of the sheets during the annealing operation they are subjected to stretching or tension of such intensity as to flatten the sheets as they are softened during annealing and to hold them flat during their passage through the annealing and cooling zone of the chamber. As illustrated, this mechanism includes a track 17 which is parallel to the track 11 and is positioned in line with and below the channel or slot 9 communicating with the bottom of the annealing chamber. A hanger 18 having sheet engaging prongs 19 is secured to the lower edges of the sheets 16 and an inverted trolley 20 having a roller 21 engaging the bottom of the track 17 is connected to the inverted hanger 18 by a suitable connection preferably including a helical spring 22. The springs 22 are of such strength that the sheets stretched there-

by will be flattened when soft and will be held taut and rigid during the entire annealing and cooling operation. In this way the buckles and other unevenesses due to rolling are obliterated and the buckling during cooling is overcome. The sheets can be moved through the annealing chamber at the desired rate of speed by shifting the trolleys along the associated tracks.

It will be apparent that the sheets during annealing are perfectly ventilated, thus permitting the free escape of occluded gases. This results in finished sheets having extremely low magnetic losses. Absolute flatness of the finished sheets is insured by positively maintaining the sheets taut and rigid during the entire annealing and cooling operation. Obviously, the sheets can be passed through the furnace in groups of two, as illustrated, or they may be pasted singly therethrough.

What I claim as new and desire to secure by Letters Patent is:

1. An annealing furnace formed of two oppositely positioned sections provided with recesses in their inner faces cooperating to form an annealing chamber, said sections being spaced so as to provide slots extending through the roof and floor of said furnace and communicating with said chamber, a track associated with the slot in said roof and a trolley movable along said track and extending into said chamber for supporting a sheet to be annealed, a second track positioned beneath the slot in said floor and mechanism movable along said second track and engaging said sheet for applying a stretching force thereto.

2. An annealing furnace formed of two oppositely positioned sections provided with recesses in their inner faces cooperating to form an annealing chamber, said sections being spaced so as to provide slots extending through the roof and floor of said furnace and communicating with said chamber, means associated with the slot in said roof for supporting a sheet to be annealed, and means associated with the slot in the floor to apply a stretching force to said sheet.

3. An annealing furnace formed of two oppositely positioned sections provided with recesses in their inner faces cooperating to form an annealing chamber, said sections being spaced so as to provide slots extending through the roof and floor of said furnace and communicating with said chamber, means associated with each slot to support a sheet to be annealed in the furnace and apply a stretching force to the opposite end of said sheet.

4. An annealing furnace formed of two oppositely positioned sections provided with recesses in their inner faces cooperating to form an annealing chamber, said sections being spaced so as to provide slots extending

- through the roof and floor of said furnace and communicating with said chamber, means associated with the slot in said roof for supporting a sheet to be annealed, and
 5 means associated with the slot in the floor to apply a stretching force to said sheet, said first means including a track, a trolley having a roller engaging on said track and a hanger connected to said trolley and ex-
 10 tending into said chamber provided with means for engaging the top of the sheet.
6. An annealing furnace formed of two oppositely positioned sections provided with recesses in their inner faces cooperating to
 15 form an annealing chamber, said sections being spaced so as to provide slots extending through the roof and floor of said furnace and communicating with said chamber, means associated with the slot in said roof
 20 for supporting a sheet to be annealed, and means associated with the slot in the floor to apply a stretching force to said sheet, said second means including a track, a trolley having a roller engaging said track from
 25 below and a hanger extending into said chamber for engaging the bottom of the sheet, and a spring between said trolley and hanger.
7. An annealing furnace formed of two oppositely positioned sections provided with recesses in their inner faces cooperating to
 30 form an annealing chamber, said sections being spaced so as to provide slots extending through the roof and floor of said furnace and communicating with said chamber, means associated with the slot in said roof
 35 for supporting a sheet to be annealed, and means associated with the slot in the floor to apply a stretching force to said sheet,
- 40 said first means including a track, a trolley having a roller engaging on said track and a hanger connected to said trolley and extending into said chamber provided with means for engaging the top of the sheet,
- 45 said second means including a track, a trolley having a roller engaging said track from below and a hanger extending into said chamber for engaging the bottom of the sheet, and a spring between said trolley and
 50 hanger.
8. An annealing furnace formed of two oppositely positioned sections provided with recesses in their inner faces cooperating to
 55 form an annealing chamber, said sections being spaced so as to provide slots extending through the roof and floor of said furnace and communicating with said chamber, means associated with the slot in said roof for supporting a sheet to be annealed,
 60 and means associated with the slot in the floor to apply a stretching force to said sheet, said chamber having internal heating means.
9. An annealing furnace formed of two oppositely positioned sections provided with
- recesses in their inner faces cooperating to form an annealing chamber, said sections being spaced so as to provide slots extending through the roof and floor of said furnace and communicating with said chamber, means associated with the slot in said roof for supporting a sheet to be annealed, and means associated with the slot in the floor to apply a stretching force to said sheet, said chamber being of variable length de-
 75 pending upon the number of oppositely as-
 80 sociated sections assembled end to end to give the desired length.
- In testimony whereof, I have hereunto subscribed my name this 14th day of Sep- 80
 tember, 1928.
